UNITED STATES PATENT OFFICE.

CLARENCE MINOR McCLURE, OF DETROIT, MICHIGAN, ASSIGNOR TO NYAL CO., OF DETROIT, MICHIGAN, A CORPORATION OF MICHIGAN.

DESIGN FOR A BOTTLE.

49,581.

Specification for Design.

Patented Aug. 29, 1916.

Application filed May 9, 1916. Serial No. 96,453. Term of patent 14 years.

To all whom it may concern:

Be it known that I, CLARENCE MINOR McCLURE, a citizen of the United States of America, residing at Detroit, in the county of Wayne and State of Michigan, have invented a new, original, and ornamental Design for Bottles, of which the following is a specification, reference being had to the accompanying drawings, forming a part of the same.

Figure 1 is a front view of a bottle embodying my design; Fig. 2 is a side view, and Fig. 3 a sectional view on the lines 3—3 of Fig. 1.

My design consists in a novel and original shape, for a bottle.

What I claim and desire to secure by Letters Patent is:

The ornamental design for a bottle substantially as shown and described.

CLARENCE MINOR McCLURE.
